UNITED STATES PATENT OFFICE

2,180,782

ROTARY PRINTING PRESS

Isidor Tornberg, Plainfield, N. J., assignor to
Wood Newspaper Machinery Corporation,
New York, N. Y., a corporation of Virginia

Original application June 9, 1936, Serial No.
84,244. Divided and this application March
17, 1937, Serial No. 131,277

3 Claims. (Cl. 101—178)

This is a division of my application for patent on a Printing press, Serial No. 84,244, filed June 9, 1936.

The principal objects of the invention are to provide a convenient drive whereby the shifting of a single gear on each impression cylinder of color press will reverse the printing couple so that the couples may be driven both in one direction, or in the other direction, or in opposing directions, as desired, and to provide compact gearing so that in printing four colors there is a minimum difficulty experienced in maintaining register between the four printing cylinders.

Other objects and advantages of the invention will appear hereinafter.

Reference is to be had to the accompanying drawing, in which

Fig. 1 is an end view of the driving arrangement for a color unit constructed according to this invention;

Fig. 2 shows one combination of gearing in which the top sides of the impression cylinders are running toward each other;

Fig. 3 shows the opposite combination where the top sides of the impression cylinders are running away from each other;

Fig. 4 shows a combination where both impression cylinders turn to the left, as viewed from the top, and

Fig. 5 shows a combination where both impression cylinders turn to the right, as viewed from the top.

A color unit is shown printing on two webs in two colors. It includes two separated impression cylinders 3 and 4 and in this instance four plate cylinders 5, 6, 7 and 8 and suitable ink motions are used.

While the impression cylinders 3 and 4 are relatively close together there is sufficient clearance provided between them through which two webs, as for example W² and W³ may be led. It is obvious that no printing is done on these two webs when they are led between the impression cylinders, as shown. The purpose is merely to permit the placement in the desired location of other webs which are being printed. A single web can be printed in four colors, if desired, by leads not shown.

Bevel gears 23^a and 24^a are secured to a vertical shaft 22 and mesh with bevel gears 25 and 26 respectively, the latter two gears being carried on shafts 27 and 28. Intermediate gears 29 and 30 are secured to the shafts 27 and 28 respectively and mesh with gears 31 and 32 as desired. These last two gears are slidably splined

to the impression cylinders 4 and 3 respectively so that they can be moved axially and drive these two cylinders. In the case of the intermediate gear 30, on the shaft 28, it can mesh with the gear 32 on the cylinder 3 in the position shown in Fig. 2 but can also mesh with the gear 31. Thus, it will be seen that a reversible drive may be provided for the impression cylinders 3 and 4. This driving arrangement provides a very flexible device which may be used to drive the impression cylinders 3 and 4 in the various combinations shown.

An arrangement is shown where two colors are added to one side of each of the two webs W¹ and W².

A new and useful arrangement is employed whereby additional colors may be applied to the webs substantially at will and a simple, inexpensive and compact arrangement is shown for driving the press rolls.

Having thus described my invention and the advantages thereof, I do not wish to be limited to the details herein disclosed, otherwise than as set forth in the claims, but what I claim is:

1. The combination of a printing unit in two separated parts, each comprising an impression cylinder having studs and a plurality of printing cylinders, sliding gears on the studs of said impression cylinders, means for driving said gears in opposite directions, and two shafts between the impression cylinders, said sliding gears on said studs being adapted to move into mesh with either of said gears to render it possible to run either impression cylinder in either direction.

2. The combination with a printing unit including two impression cylinders in juxtaposition, plate cylinders for cooperating with the impression cylinders, two driving gears running in opposite directions, and one gear mounted on each impression cylinder, either or both of which gears may be moved into mesh with either of said two driving gears to obtain the desired direction of rotation of said impression cylinders.

3. The combination with a printing unit including two impression cylinders in juxtaposition, plate cylinders for cooperating with the impression cylinders, two driving gears running in opposite directions, and one gear mounted on each impression cylinder, either or both of which may be moved into mesh with either of said two driving gears to obtain the desired direction of rotation and means for leading webs between the two impression cylinders.
